UNITED STATES PATENT OFFICE.

FURMON S. SMITH, OF GRANTS PASS, OREGON.

WRENCH.

1,291,214.

Specification of Letters Patent. Patented Jan. 14, 1919.

Application filed May 11, 1918. Serial No. 233,866.

To all whom it may concern:

Be it known that I, FURMON S. SMITH, a citizen of the United States, residing at Grants Pass, in the county of Josephine and State of Oregon, have invented certain new and useful Improvements in Wrenches, of which the following is a specification, reference being had to the accompanying drawings.

10 This invention relates to certain new and useful improvements in wrenches, and has for its primary object to provide means adapted to that type of wrench having a screw adjustable sliding jaw whereby a positive binding pressure of the jaw on the object may be obtained and the jaw then securely locked against movement.

It is another object of the invention to provide an improved tool of the character 20 above stated whereby the same may be utilized as in the manner of the ordinary wrench, and in addition as a vise, pincers or analogous tool.

It is also a further general object of my 25 invention to improve and simplify the construction of wrenches of the sliding jaw type whereby the same are rendered of greater utility as well as more effective and reliable in practical use, though without greatly complicating the construction or materially increasing the manufacturing cost of such tools.

With the above and other objects in view, the invention consists in the improved combination, construction and arrangement of 35 the several parts as will be hereinafter more fully described, subsequently claimed and illustrated in the accompanying drawing in which similar reference characters designate 40 corresponding parts throughout the several views, and wherein:

Figure 1 is a side elevation of a wrench illustrating the preferred embodiment of the invention;

45 Fig. 2 is a similar view partly in section and showing the sliding jaw locked in binding engagement upon an object;

Fig. 3 is a section taken on the line 3—3 of Fig. 2; and

50 Fig. 4 is a section taken on the line 4—4 of Fig. 2.

Referring in detail to the drawing, 5 designates the shank of the wrench having a fixed or stationary jaw 6 formed on one of its ends. 7 designates the movable or adjustable wrench jaw opposed to the stationary

jaw 6 and having the spaced laterally extending yokes 8 loosely engaged on the wrench shank 5. The jaw 7 is further provided with a threaded bore to receive the 60 adjusting screw 9, said screw having the usual knurled disk or finger piece 10 whereby said screw may be conveniently rotated.

To the other end of the shank 5 the longitudinally extending side plates 11 are securely riveted at one of their ends as indicated at 12. These plates at their other ends are of increased width and between the same the channel-shaped arm 14 of a handle member 13 extends. A rivet 15 is fixed in the 70 side plates 11 and extends loosely through the spaced portions of the channel-shaped arm 14 whereby the handle member is retained between the side plates for pivotal movement. The arm 14 at its inner end is 75 curved as at 16, and the medial portion of this arm is formed with an inwardly projecting lug 17 for a purpose which will be presently stated.

A second handle member 18 also has a 80 channel-shaped arm 19 extending between the side plates 11, and this arm is pivotally engaged upon the rivet 20 connecting said plates adjacent to the ends of the wrench shank 5. The side portions of the channel-shaped arm 19 at the pivoted end thereof are laterally extended as at 21 and project over the rounded end 16 of the arm 13, said extensions having their inner edges concaved as shown at 22. These lateral extensions at 90 their ends are angularly bent toward each other and between the opposed edges thereof a screw 23 is rotatably engaged. This screw also has threaded engagement in a shiftable nut 24 arranged between the side 95 portions of the arm 14 of the handle member 13 and having frictional engagement therewith. A wire spring 25 has its terminals connected to the handle members 13 and 18 and is provided with a single centrally 100 formed coil 26.

The lower end of the jaw adjusting screw 9 is rotatably engaged between the lateral extensions 21 of the handle member 18.

In the operation of the device, the screw 9 105 is first rotated to move the jaw 7 upon the wrench shank and into engagement with the object disposed between said jaws. The handle members 13 and 18 are then forced toward each other and the end edges 16 of 110 the channel-shaped arm 14 coacting with the concave edges 22 of the extension 21 on the

other handle member, further urges the adjustable jaw upon the object so that said jaw will have a binding, gripping engagement with the object. The screw 23 is now rotated, and when the end of this screw comes into bearing contact against the arm 19 of the handle member 18, the nut 24 will move laterally on the screw and into contact with the inwardly projecting lug 17 on the arm 10 of the handle member 13. The screw and the nut will thus hold the handle members against relative lateral movement under the action of the spring 25, and the jaw 7 will also be held against inward shifting movement on the wrench shank. Thus, a greater binding or gripping pressure of the jaw on the object can be obtained than would be possible simply by the adjustment of the screw 9.

20 From the foregoing description taken in connection with the accompanying drawing, the construction, manner of operation and several advantages of the invention will be clearly and fully understood. The improved 25 tool may be used in the manner of the ordinary wrench, and also as a vise, pincers or analogous tool employed to securely grip and hold an object. The present improvement can be employed in conjunction with 30 the well known monkey wrench now in general use and will not add materially to the manufacturing cost thereof. It is, of course, apparent that I may, however, provide wrench jaws of other forms than those illustrated in the drawing, as for instance, the jaws may be formed with their opposed faces angularly extending with respect to the axis of the wrench shank. They also can be roughened or serrated if desired so as to obtain 35 a more secure gripping engagement with the object. Owing to the simple construction of the device and the compact arrangement of its several parts, the tool may be easily adjusted and manipulated in corners or other close places.

40 While I have herein shown and described the preferred construction and arrangement of the various parts, it is to be understood that the device is susceptible of many 45 modifications therein and I therefore reserve the privilege of adopting all such legitimate changes as may be fairly embodied within the spirit and scope of the invention as claimed.

50 55 I claim:—

1. A wrench comprising a shank having

a fixed jaw on one end, an adjustable jaw on said shank, pivotally mounted handle members, adjusting means for the latter jaw connected to one of said handle members, and manually operable means to hold the handle members against relative movement and retain the adjustable jaw in engagement with an object, said means including permanently engaged relatively movable parts coacting with the respective handle members.

2. A wrench comprising a shank having a fixed jaw on one end, an adjustable jaw on said shank, channel-shaped pivotally mounted handle members, adjusting means for the latter jaw connected to one of said handle members, and means for locking said handle members against pivotal movement to retain the adjustable jaw in gripping engagement upon an object, said means including permanently engaged relatively movable parts housed within the channels of the handle members and coacting with the respective handle members.

3. A wrench comprising a shank having a fixed jaw on one end, an adjustable jaw on said shank, longitudinally extending side plates fixed to the shank, a pair of handle members pivotally mounted between 85 said plates, one of said handle members having a lateral extension on its pivoted end with which the other handle member coacts, an adjusting screw for the latter jaw connected to said lateral extension of the 90 handle member and through the medium of which said jaw is shifted toward the fixed jaw when the handle members are moved toward each other, a spring urging the handle members apart, a screw rotatably 95 mounted in the lateral extension of the handle member and a nut threaded upon said screw and adapted to be moved thereby into binding engagement with the other of the handle members, said screw coacting 100 with the first named handle member and in conjunction with the nut preventing the pivotal movement of the handle members to their normal positions whereby the adjustable jaw is retained in gripping engagement with the object.

In testimony whereof I hereunto affix my signature in the presence of two witnesses.

FURMON S. SMITH.
